PATENTED DEC. 5, 1905.

G. ZIMERMANN.

LOOM FOR WEAVING DOUBLE PILE FABRICS

APPLICATION FILED NOV. 5, 1904.

UNITED STATES PATENT OFFICE.

GEORGE ZIMERMANN, OF PHILADELPHIA, PENNSYLVANIA.

LOOM FOR WEAVING DOUBLE-PILE FABRICS.

No. 806,729.

Specification of Letters Patent.

Patented Dec. 5, 1905.

Application filed November 5, 1904. Serial No. 231,550.

To all whom it may concern:

Be it known that I, GEORGE ZIMERMANN, a citizen of the United States, residing in Philadelphia, Pennsylvania, have invented certain 5 Improvements in Looms for Weaving Double-Pile Fabrics, of which the following is a specification.

My invention relates to that class of pile-fabric-weaving looms in which two independent backing-webs are produced one above and the other below, a series of interposed separator bars or plates, the pile-forming warp-threads being shedded back and forth in the spaces between these bars or plates, so as to engage first with one backing-web and then with the other and the crossing threads which connect the two backing-webs being subsequently severed midway between said backing-webs, so as to produce two independent fabrics, each with a cut-pile face.

The object of my invention is to simplify the construction and improve the operation of looms of this class.

In the accompanying drawings, Figure 1 is a longitudinal section of sufficient of a loom to illustrate my present invention. Fig. 2 is a perspective view of part of the loom, and Fig. 3 is a perspective view illustrating a modification of the invention.

Reference being had in the first instance to Fig. 1 of the drawings, 1 represents the breast-beam of the loom, and 2 part of the swinging lay with the usual reed 3 and shuttle-race 4.

35 The pile-forming warp-threads 5 are controlled by the harness-cords 6 of a suitable jacquard apparatus, the binding warp-threads 7 of the upper backing fabric are controlled by heddles 8, and the binding warp-threads 9 of the lower backing fabric are controlled by heddles 10, and in addition to these heddles there is another heddle 11, which controls a series of rods or bars 12, the rear ends of these bars being pivoted at 13 to the bars 45 of the heddle 11, and their forward ends being provided with pivot-pins 14, which are adapted to slots 14^a in the inner ends of the separator bars or plates 15, whose forward ends are secured in slots in a bar 16, which 50 is properly mounted upon the top of the breast-beam 1. There are as many of these separator bars or plates 15 as may be necessary to properly support the backing fabrics, there being, by preference, one supporting

bar or plate for each longitudinal row of 55 pile in the fabric to be produced, and the outer end of each bar 15 is slotted, as shown at 17, for the reception of the cutting edge of a knife 18, which is secured to a bar 19, having a portion suitably guided in a transverse groove of the bar 16, so that the knife can be traversed back and forth across the loom in order to sever the warp-threads which extend from one backing fabric to the other.

In the present instance I have shown pile- 65 warp threads having six threads in a set, three of these threads being embedded in the upper backing fabric and the other three being embedded in the lower backing fabric, the warp-threads of each fabric being securely bound by means of weft-threads 20, which are interwoven with said warp-threads and with the binding warp-threads 7 or 9, the pile warp-threads being carried from one backing fabric to the other, in accordance 75 with the color requirements of the pattern. Hence, in a pattern requiring six colors only three pile warp-threads will be contained in each backing fabric.

If desired, a stuffer warp thread or threads 80 may also be combined with each backing fabric in order to impart additional body to the latter, such stuffer warp-threads being controlled by suitable heddles.

The purpose of the rods or bars 12, which 85 connect the heddle 11 and separator-plates 15, is to aid in directing the weft-threads 20 into the upper or lower backing fabrics, as required, and to relieve the warp-threads in large measure from the strain of such duty. 90 By pivoting said rods or bars 12 at one end to the heddle at the opposite end to the separator-plates their free movement can be effected without imposing any restraint upon the rising-and-falling movement of the heddle, and by permitting back-and-forth movement of the pivotal connection between each bar 12 and its corresponding separator-plate by reason of the slot 14^a longitudinal strain 95 upon the bar 12 or its connections, due to the constantly-varying distance between its opposite pivotal connections, is overcome and the bending or buckling of the bars which might otherwise be caused is effectually prevented. Instead of providing a slotted connection between each bar 12 and its corresponding separator-plate 15 the reverse construction may 100 be adopted—that is to say, the bar 12^a may be

slotted, as at 21, for the reception of the pivot-pin 22, whereby it is connected to the heddle 11^a, as shown, for instance, in Fig. 3.

Having thus described my invention, I claim 5 and desire to secure by Letters Patent —

1. The combination, in a loom for weaving double-pile fabrics, of the weaving mechanism, separator-plates interposed between the upper and lower backing fabrics and having 10 rigid connection with a rigid transverse bar of the loom, weft-thread-directing bars having pivotal connection with said separator-plates, and a controlling-heddle for said director-bars with which the latter also have pivotal 15 connection, substantially as specified.
2. The combination, in a loom for weaving double-pile fabrics, of the weaving mechanism, separator-plates interposed between the upper and lower backing fabrics, weft-thread- 20 directing bars having pivotal connection with said separator-plates, and a controlling-heddle for said director-bars and with which the latter also have pivotal connection, one of said pivotal connections being slotted, substantially 25 as specified.
3. The combination, in a loom for weaving double-pile fabrics, of weaving mechanism, separator-plates interposed between the upper and lower backing fabrics and having rigid 30 connection with a rigid transverse bar of the loom and also slots open at the outer ends of the plates, and a transversely-moving knife

whose cutting edge enters said slots, substantially as specified.

4. The combination in a loom for weaving 35 double-pile fabrics, of weaving mechanism, separator-plates interposed between the upper and lower backing fabrics, said separator-plates having slots open at the outer ends, a bar upon which said separator-plates are 40 mounted, and a transversely-movable cutting-knife also mounted on said bar and having a cutting edge which enters the slots in the separator-plates, substantially as specified.

5. The combination, in a loom for weaving 45 double-pile fabrics, of weaving mechanism, separator-plates interposed between the upper and lower backing fabrics and having rigid connection with a rigid transverse bar of the loom, said plates also having open-ended slots 50 at their front ends, a transversely-movable knife having a cutting edge entering said slots, director-bars having pivotal connection with the inner ends of the separator-plates, and a controlling-heddle for said bars also 55 having pivotal connection therewith, substantially as specified.

In testimony whereof I have signed my name to this specification in the presence of two subscribing witnesses.

GEORGE ZIMERMANN.
